UNITED STATES PATENT OFFICE.

CYRUS F. LOGAN, OF WASHINGTON, DISTRICT OF COLUMBIA, ASSIGNOR TO FIBER PRODUCTS CORPORATION, A CORPORATION OF DELAWARE.

FIBER-TREATING MACHINE.

1,249,788.

Specification of Letters Patent. Patented Dec. 11, 1917.

Application filed July 17, 1915. Serial No. 40,386.

To all whom it may concern:

Be it known that I, CYRUS F. LOGAN, a citizen of the United States, residing in the city of Washington, in the District of Columbia, have invented certain new and useful Improvements in Fiber-Treating Machines, of which the following is a specification.

This invention relates to improvements in fiber treating machines for the treating of fibrous plants, leaves, and the like in order to obtain the fibers therefrom.

One of the main objects of the present invention is to provide a support or bed for the fibers while being treated which will have a positive rate of movement.

Another object of the invention is to provide a positively driven bed which will cooperate in advancing the fibers in their path of movement through the machine.

Still another object of the invention is to provide a system whereby the power required for operation is comparatively small and whereby the apparatus can be so arranged that it will occupy a comparatively small amount of space.

To this end, a bed or support is provided whereby the fibers being passed through the machine for treatment will be supported by a plurality of rolls, certain of said rolls serving as beds with which brushes coat in the treatment of the fibers, and others of said rolls serving as beds with which pressure rolls coat in the treatment of the fibers, the arrangement preferably having one or more pressure rolls interposed between each two successive brushes. Due to the positive rotation of such bed-forming rolls, the pressing and advancing treatment exercised on the fibers by such rolls will be regular and even throughout. Furthermore the use of such system of rolls for supports permits the arrangement of the apparatus in a compact machine which will occupy a comparatively small amount of space. Furthermore, to form a support for the fibers or rather a bed plate for the fibers while they are being treated by the several brushes, there are provided similar rolls which, however, are equipped with disks, the disks serving as the tines of a comb. These rolls provided with the disks form rotating

combs and the disks thereof pass in between the bristles of the brushes to coat with the same in the treatment of the fiber.

These rotating combs not only subject the fibrous plants, being treated, to a positive decorticating action and spreading action, but in addition, due to their continuous operation, prevent the collection of foreign material in the path of movement of the fibers.

A further object of the invention is to provide a system for treating fibers whereby the increased length of the fibers, caused by their treatment while being advanced, will be taken up by a dragging action which will stretch out and straighten out any piling up that tends to form, due to such lengthening of the fibers.

A still further object of the invention is to provide a system for treating fibers in which rotatable brushes are provided for treating the fibers, the engaging portions of the brushes moving in a direction opposite to the path of movement of the fibers, and in which system there is provided an advancing bed for feeding the fibers along their path of movement, and a guiding conveyer to which the front ends of the fibers are attached, said advancing bed coöperating with the conveyer to advance said fibers so that the strain created in the fibers by the oppositely moving brushes will not be localized at the front ends of the fibers, but will be distributed and thus prevent tearing or fracturing of the fibers at their front ends.

And still another object of the invention is to provide an arrangement whereby the brushes are divided into tufts, and the fibers divided into a series of strands, each strand of fibers being confined along a certain path of movement to the exclusion of another strand of fibers and treated by one of the tufts of a brush, each strand being treated by an individual tuft.

These and other features, capabilities and advantages of the invention will appear from the subjoined detail description of one specific embodiment thereof, illustrated in the accompanying drawings, in which—

Figure 1 is a fragmental view in section on the line 1^x—1^x of Fig. 2, showing the

positively rotated rolls forming the bed for the fibers and also showing one of the brushes for treating such fibers.

Fig. 2 is a fragmental view showing one of the brushes partly in section along the line 2^a—2^a of Fig. 1, and also showing one of the pair of opposing rolls partly in section along the line 2^b—2^b of Fig. 1.

Fig. 3 is a diagram showing the system of rolls and brushes together with the driving connection.

Fig. 4 is a fragmental view partly in section along the line 4^x—4^x of Fig. 2.

Fig. 5 is a plan view of one of the washers of a rotating comb.

Fig. 6 is a section along the line 6^x—6^x of Fig. 1.

Fig. 7 is a plan view of one of the disks of the rotating comb.

Fig. 8 is a section along the line 8^x—8^x of Fig. 7.

Figs. 9, 10 and 11 are diagrammatic views illustrating the crowding action that takes place in the strands with the resulting piling up and the manner of straightening out such piling up.

In the embodiment shown, there are provided two sectional side frame members 11, 11 connected to one another by lower cross pieces 12 substantially L-shaped in cross section and upper cross pieces 13 substantially T-shaped in cross section. The side members 11 are provided immediately above the cross pieces 12 with rail members 14 on which the hank bars, to which the fibrous plants are clamped, travel. Alongside of the rail members 14 and mounted on the cross pieces 12 are provided chain guiding brackets 15, 15 to guide the conveyer chains 16, 16, to which chains the hank bars are secured and by means of which they are drawn through the apparatus as clearly illustrated and described in my copending application, Serial No. 875,454, filed December 4, 1914.

Alongside of the chain guiding brackets 15 and secured to the cross pieces 12, there are provided rail members 17 each having an upper flange 18 and a lower flange 19 extending inwardly.

The side members 11 are each provided with a series of pockets 20 containing bearings 21 for the shafts 22 of the pressure rolls 23, the pockets 20 being provided with springs 24 to normally maintain the bearings 21 in their extreme lower positions. The rolls 23 are rotated by the friction of the fibrous plants and fibers passing between them or by contact with the rotating rolls hereinafter to be described. The side members 11 are also each provided with a series of enlargements 25 in which there are provided pockets 26 containing bearings 27 for the shafts 28 of the brushes 29. The pockets 26 are likewise provided with springs 30 to

normally maintain the bearings 27 in their extreme lower positions. The brushes 29 are positively driven, their shafts 28 being provided with pulleys 31 (Fig. 2) properly connected by a belt 32 with a suitable source of power not shown.

The shafts 22 are each provided with collars 33 near their ends and the shafts 28 are each provided with mutilated disks 34 near their ends with which the hank bars engage to raise the shafts 22 and 28 and thereby the rolls 23 and brushes 29 respectively to permit the passage of such hank bars. In the present arrangement between each two successive brushes 29 are interposed two pressure rolls 23, some of the brushes being disposed below the path of travel of the fibrous plants (see Fig. 3).

Below each pressure roll 23 there is provided a positively driven roll 35 and opposite to each brush 29 and which is to form a bed plate with which the brush 29 co-operates, there is provided a rotating comb 36, between which brushes 29 and rotating combs 36 the fibrous plants travel.

The positively driven rolls 35 are each mounted on a shaft 37 carried by brackets 38 secured to the lower flanges 19 of the roll members 17. The ends of the shafts 37 are provided with sprocket wheels 39 which are engaged by the sprocket chains 40 by means of which the rolls 35 are rotated. The rolls 23 in their extreme lower positions are each disposed in direct contact with the rolls 35 so that they in turn will be rotated by the rolls 35 by such contact when they are not rotated by contact with the fibrous plants being drawn through the machine.

The rotating combs 36 are mounted on shafts 41 carried by bearing plates 42 secured to the rail members 17 above the lower flanges 19, the shafts 41 each having gears 43 at their ends adjacent to the bearing plates 42 in mesh with gears 44 secured at one of the ends of the stub shafts 45 mounted in brackets 46 secured to lower sides of the lower flanges 19, the sprocket wheels 47 being mounted on the other ends of said stub shafts 45 and in engagement with sprocket chains 40 so that the rotating combs 36 and the rolls 35 both have rotation transmitted to them by means of the same sprocket chains 40.

The rotating combs each comprise a series of washers or collars 48 fixed to its shaft 41, the washers being shown in Figs. 5 and 6 such washers spacing apart the disk members 49 (shown in Figs. 7 and 8) which form the tines of the comb 35 which disk members are likewise fixed in place.

The brushes do not have rotation transmitted to them from the chains 40 but from the belt 32 and such brushes rotate at a considerably fast rate of speed compared to the

rotation of the rolls 35 and rotating combs 36. The rotation of the rolls 35 is predetermined and may be set to different speeds, the desired speed being set according to the constituency of the plants being treated, so that the chains may either exercise the same draft on the fibers as the rolls 35 or else a greater draft.

From the diagram illustrated in Fig. 3, it will be seen that all the rolls 35 will rotate in the same direction, that is, to transmit an advancing movement to the fibers being treated which is in the same direction as the movement of the chains 16. Consequently, the rolls 23 which are idlers will rotate in the opposite direction to the rolls 35. On the other hand, the brushes 29 and the rotating combs 36 are rotated in directions opposite to those of the rolls 23 and 35 respectively.

The speed of the rolls 35 and the rotating combs 36 and consequently the movement of the sprocket chains 40 may be regulated by the cone pulleys 50 interposed between the driving pulley 51 and the sprocket chains 40.

The rotating combs 36 coöperating with the brushes 29 form a bed for such brushes, and furthermore clean such brushes. Due to their constant rotation, foreign material cannot very well collect on the rotating combs 36 since the combs will constantly discharge any material that would collect on the same.

The rotating combs 36 furthermore exercise a decorticating and spreading action on the fibers being treated, and both divide the brushes into a series of tufts (see Fig. 2), and also divide the plants into a series of strands, a strand for each tuft, so that the action of each tuft will be confined to a certain strand.

As illustrated in Figs. 9, 10 and 11, the fiber strands F are secured to the hank-bars 52. The hank bars 52 are in the lead, being attached to the conveyer chains 16 (shown in Figs. 1, 2 and 3). In some instances the rolls 15 are driven to advance the fibers just a trifle faster than the conveyer chains 16 advance the hank bars, in which case the opposing rolls 23 and 35 would really be the members which were actively engaged in advancing the fibers F, and thus the strain created in the fibers by the pulling action of the hank bars would entirely be overcome, whereas in other cases the strain would at least be partly relieved according to the speed of the rolls 23 and 35 relative to the speed of the conveyer chains 16.

Due to the treatment of the rolls 23 and 35, and that of the brushes 29 coöperating with the combs 36, the fibers F will stretch out and become longer, and thus, by means of the reverse rotation of the brushes 29,

and their respectively opposing combs 36, the strands will pile up immediately behind each brush so that the fibers will buckle upward as illustrated in Figs. 9, 10 and 11 where the brushes are disposed above the path of movement of the fibers and buckle downward as illustrated in Fig. 11, wherever the brushes are located below the path of movement of the fibers F. Due to the reverse rotation of the brushes 29 and rotating combs 36, the fibers will slip backward between the rolls 23 and 35, and whenever their tail ends are entirely free of the rolls and acted on by the brushes and combs due to the dragging action exercised by the brushes and combs, the piling up of the strands that existed in such tail ends will be straightened out.

It is obvious that various changes and modifications may be made to the details of construction without departing from the general spirit of the invention.

I claim:

1. In a fiber treating machine, a frame, a conveyer mounted to travel on said frame on which conveyer the fibers are attached to be thereby drawn through the machine, a bed for supporting the fibers while being drawn by said conveyer, said bed comprising a plurality of positively driven rolls, between which the fiber may be drawn; a means for simultaneously driving all of the said rolls, and independent driving means for said conveyer so that the rolls may be driven at a different rate of speed than the conveyer.

2. In a fiber treating machine, a frame, a conveyer mounted to travel on said frame on which conveyer the fibers are attached to be thereby drawn through the machine, a bed for supporting the fibers while being drawn by said conveyer, said bed comprising a plurality of rolls having their axes disposed transversely of the path of movement of said fibers, said rolls being positively driven in the direction of the path of movement of the conveyer so as to assist in advancing the fibers, and independent driving means for said rollers and said conveyer so that different rates of speed relative to one another may be transmitted to said rollers and conveyer.

3. In a fiber treating machine, a frame, a conveyer mounted to travel on said frame on which conveyer the fibers are attached to be thereby drawn through the machine, a bed for supporting the fibers while being drawn by said conveyer, said bed comprising a plurality of positively driven rolls between which the fiber may be drawn and fiber treating brushes opposite to certain of said rolls, between which fiber treating brushes and said oppositely disposed rolls, the fibers pass, such oppositely disposed rolls serving

as beds with which said brushes coact, a driving means for all of said rolls, and independent driving means for said conveyer so that the rolls may be driven at a different rate of speed than the conveyer.

4. In a fiber treating machine, a frame, a conveyer mounted to travel on said frame on which conveyer the fibers are attached to be thereby drawn through the machine, a bed for supporting the fibers while being drawn by said conveyer, said bed comprising a plurality of positively driven rolls, and fiber treating brushes opposite to certain of said rolls, between which fiber treating brushes and said oppositely disposed rolls the fibers pass, such oppositely disposed rolls serving as beds with which said brushes coact, said oppositely disposed rolls being positively driven and being provided with disks to form rotating combs to coact with the brushes in the treatment of the fibers.

5. In a fiber treating machine, a frame, a conveyer mounted to travel on said frame on which conveyer the fibers are attached to be thereby drawn through the machine, a bed for supporting the fibers while being drawn by said conveyer, said bed comprising a plurality of rolls having their axes disposed transversely of the path of movement of said fibers, and fiber treating brushes opposite to certain of said rolls, between which fiber treating brushes and said oppositely disposed rolls the fibers pass, such oppositely disposed rolls serving as beds with which said brushes coact, said oppositely disposed rolls being positively driven and being provided with disks to form rotating combs to coact with the brushes in the treatment of the fibers.

40 6. In a fiber treating machine, a frame, a conveyer mounted to travel on said frame on which conveyer the fibers are attached to be thereby drawn through the machine, a bed for supporting the fibers while being drawn by said conveyer, said bed comprising a plurality of positively driven rolls, fiber treating brushes opposite to certain of said rolls, between which fiber treating brushes and said oppositely disposed rolls the fibers pass, such oppositely disposed rolls serving as beds with which said brushes coact, said oppositely disposed rolls being positively driven and each comprising a shaft, a plurality of disks mounted on said shaft, and a plurality of washers mounted on said shaft and spacing said disks from one another to form a rotating comb to coact with its oppositely disposed brush in the treatment of the fibers.

60 7. In a fiber treating machine, a frame, a conveyer mounted to travel on said frame on which conveyer the fibers are attached to be thereby drawn through the machine, a bed for supporting the fibers while being drawn

by said conveyer, said bed comprising a plurality of rolls having their axes disposed transversely of the path of movement of said fibers, fiber treating brushes opposite to certain of said rolls, between which brushes and said oppositely disposed rolls the fibers pass, and pressure rolls opposite to others of said rolls, the rolls opposite to said brushes each being provided with disks to form rotating combs with the brushes in the treatment of the fibers and being rotated in a direction opposite to the path of movement of the fibers being treated while the rolls opposite the pressure rolls are rotated in the same direction as the path of movement of the fibers being treated to assist in advancing them.

8. In a fiber treating machine, a frame, a conveyer mounted to travel on said frame on which conveyer the fibers are attached to be thereby drawn through the machine, a bed for supporting the fibers while being drawn by said conveyer, said bed comprising a plurality of rolls between which the fibers may be drawn having their axes disposed transversely of the path of movement of the fibers, and fiber treating brushes opposite to certain of said rolls, between which fiber treating brushes and said oppositely disposed rolls the fibers pass, such oppositely disposed rolls serving as beds with which said brushes coact, all of said rolls being positively driven and said brushes also being driven but at a much faster rate of speed than said rolls.

9. In a fiber treating machine, a frame, a conveyer mounted to travel on said frame on which conveyer the fibers are attached to be thereby drawn through the machine, a bed for supporting the fibers while being drawn by said conveyer, said bed comprising a plurality of rolls having their axes disposed transversely of the path of movement of the fibers, and fiber treating brushes opposite to certain of said rolls, between which fiber treating brushes and said oppositely disposed rolls the fibers pass, such oppositely disposed rolls serving as beds with which said brushes coact, all of said rolls being positively driven and said brushes also being driven but at a much faster rate of speed than said rolls, said oppositely disposed rolls rotating in a direction opposite to the path of movement of said fibers being treated, while the other rolls rotate in the same direction as the path of movement of the fibers being treated to assist in advancing them.

10. In a fiber treating machine, a frame, a conveyer mounted to travel on said frame on which conveyer the fibers are attached to be thereby drawn through the machine, a bed for supporting the fibers while being drawn by said conveyer, said bed comprising a plurality of rolls having their axes disposed

- transversely of the path of movement of the fibers, and fiber treating brushes opposite to certain of said rolls, between which fiber treating brushes and said oppositely disposed rolls the fibers pass, such oppositely disposed rolls serving as beds with which said brushes coact, all of said rolls being positively driven and said brushes also being driven but at a much faster rate of speed than said rolls, said oppositely disposed rolls being provided with disks to form rotating combs to coact with the brushes in the treatment of the fibers and being rotated in a direction opposite to the path of movement of the fibers being treated, while the other rolls rotate in the same direction as the path of movement of the fibers being treated to assist in advancing them.
11. In a fiber treating machine, a roll co-
operating with a brush, said roll forming a bed for the fibers being treated, being positively driven, between which roll and the brush said fibers are passed, and comprising a plurality of disks, and a plurality of washers spaced between said disks to form a rotating comb to coact with the brush in the treatment of the fibers.
12. In a fiber treating machine, a frame, means for advancing the fibers through said frame, fiber treating brushes along the path of movement of the fibers, and rotating combs disposed opposite to said brushes, between which brushes and combs said fibers pass, said rotating combs forming a bed for said brushes and also forming cleaners for said brushes, the constant rotation of said combs serving to constantly discharge any foreign material that might collect on said combs.
13. In a fiber treating machine, a frame, a conveyer mounted to travel on said frame on which conveyer the fibers are attached to be thereby drawn through the machine, a bed for supporting the fibers while being drawn by said conveyer, said bed comprising a plurality of rolls having their axes disposed transversely of the path of movement of the fibers, fiber treating brushes opposite to certain of said rolls, between which fiber treating brushes and said oppositely disposed rolls the fibers pass, such oppositely disposed rolls serving as beds with which said brushes coact, all of said rolls being positively driven at the same speed and said brushes also being driven at the same speed but at a much faster rate of speed than said rolls, and means for regulating the speed of the bed-forming rolls.
14. In a fiber treating machine, a frame, a conveyer mounted to travel on said frame on which conveyer the fibers are attached to be thereby drawn through the machine, a bed for supporting the fibers while being drawn by said conveyer, said bed comprising a plurality of rolls having their axes disposed transversely of the path of movement of the fibers, fiber treating brushes opposite to certain of said rolls, between which fiber treating brushes and said oppositely disposed rolls the fibers pass, such oppositely disposed rolls serving as beds with which said brushes coact, all of said rolls being positively driven and said brushes also being driven but at a much faster rate of speed than said rolls, a continuous connection for transmitting rotation to said bed-forming rolls simultaneously, and means for regulating the speed transmitted to said continuous connection thereby to regulate the speed of said bed-forming rolls relative to the speed of said conveyer.

CYRUS F. LOGAN.
